UNITED STATES PATENT OFFICE.

HENRY FREEBOROUGH, OF FORT SCOTT, KANSAS.

KILN.

Application filed March 7, 1922. Serial No. 541,696.

This invention comprehends a new and improved construction of kiln, designed to minimize the consumption of fuel, as well as to facilitate firing the same, the invention 5 residing in the construction, combination, and arrangement of parts as claimed.

In the drawings forming part of this application, like numerals of reference indicate similar parts in the several views, and 10 wherein:

Figure 1—is a side elevation, partly in section.

Figure 2—is an end elevation.

Figure 3—is a central transverse sectional 15 view.

Figure 4—is a vertical sectional view taken through the fire boxes and combustion chambers.

Figure 5—is a plan view of the floor construction.

Referring to the drawings in detail, A and B indicate communicating kilns, each of which is identical in construction, and designed to promote the circulation of heat 25 over the entire floor area of the kiln. Each kiln has a door 10 at one end thereof which permits ready access to the interior of the kiln. Arranged adjacent each side of each kiln is a longitudinally disposed fire box 11, 30 the wall 13 of which is arranged in close proximity to the adjacent side of the kiln. The combustion chambers are indicated at 12 and arranged at the opposite sides of the structure. Access may be had to the fire box 35 11 at the outer side of the structure by opening the doors 12 shown in Figure 2, so that the products of combustion will extend along the entire length of the kiln. Arranged at each end of the kiln and transversely thereof 40 is a channel shaped member 14, while disposed between these members and equidistantly spaced therefrom is a similar member 15, the latter as well as the members 14 being in communication with the flues or 45 passages 16 beneath the floor as shown in Figure 1. Access to the channels may be had by opening the door 21. At the left hand side of Figure 3 it will be noted that the kiln A is provided with a passage 16' which opens 50 into the adjacent fire box, while at the right hand side of this figure, a similar passage 17' is shown which is adapted to open into a chimney 22. The passage 16' just described is only used when the kiln A is 55 arranged alongside of another kiln not illustrated, so that if the kiln A constituted

the outermost kiln of a plurality of kilns, the passage 16' would be dispensed with. In addition to communicating with the flues or passages 16, the channel like member 15 60 communicates with a tunnel 15' which opens to the atmosphere at one end of the structure through a door opening, which is normally closed by a door 18'. This tunnel is diagonally disposed with relation to the channel like member 15, as illustrated by dotted lines in Figure 5. Each transverse member 14 communicates with the adjacent fire box of the next kiln through the passage 17 as illustrated in Figure 3. 70

In practice, a fire is started in the fire box 11 of the kiln A by opening the doors 12 and igniting the fuel previously arranged in said fire box, whereupon the heat is directed upwardly, and thence deflected downwardly by the top of the kiln through the opening in the floor. If it is desired to only use the kiln A, one or more of the doors 19' are opened to permit a block of suitable material to be placed in the kiln to cut off the communication between the transverse member 14 and the next adjacent kiln. The heat then passes from the flues or passages 16 into the channel like member 15, and thence to the atmosphere through the tunnels 15'. On the other hand, if it is desired to utilize the heat from the kiln A with the next adjacent kiln B, the doors 18' of the tunnels are closed, whereupon the heat after passing downwardly through the floor, enters the channel like members 14 of the kiln A, circulating upwardly through the passages 17 into the fire box of the next kiln B. By causing the heat to pass from one kiln to the other through these passages 17, the work to be performed within the structure can be accomplished with a saving of time as compared to other kilns, and also with a reduction in fuel consumption. 85

While it is believed that from the foregoing description, the nature and advantages of the invention will be readily apparent, I desire to have it understood that I do not limit myself to what is herein shown and described, and that such changes may be resorted to when desired as fall within the scope of what is claimed. 100

What I claim is:

A plurality of kilns arranged side by side and forming a unitary structure, a fire box 110 extending longitudinally of each kiln and adjacent each side thereof, doors on the sides

of the structure to permit of access to said fire boxes, one wall of each box terminating in spaced relation with the top of the kiln, a floor for each kiln having openings therein, channel like members extending across each kiln adjacent the ends thereof, and communicating with the space beneath said floor, passages establishing communication between the said channel like members of one kiln and the fire box of the adjacent kiln, an additional channel like mem-

ber arranged between the first mentioned members and equi-distantly spaced therefrom, and also communicating with the space beneath said floor, a tunnel establishing communication between the last mentioned member and the atmosphere, and a door closing the outer end of each tunnel for the purpose specified.

In testimony whereof I affix my signature.

HENRY FREEBOROUGH.
